ATTORNEY

1 The right hand side panel 4 and the left hand side panel 5 extend rearwardly from the front panel 1, with the forward edge of each being exposed at the sides of the panel 1. Above the panel 1, a forward edge 6 of each panel 4, 5 slopes upwardly and rearwardly in an arcuate line, and at the top of each panel 4, 5 is an integrally formed forwardly extending arm 7 overhanging the arcuate edge 6. A metal trim strip 8 is attached to each edge 6, and each strip 8 extends upwardly from a level at the top edge of the front panel 1 to the corresponding arm 7 and then along both the under and upper edges of the arm 7.

2 front panel 1 formed of sheet material with a set back

ILLUMINATED DISPLAY CABINET

Harold J. Fitzgerald, Milwaukee, Wis., assignor to Super-
display, Inc., Milwaukee, Wis., a corporation of Wisconsin

Application December 5, 1955, Serial No. 551,047

1 Claim. (Cl. 312—128)

This invention relates to display cabinets and it more specifically resides in a cabinet having a plurality of shelves spaced one above the other in which the shelves are disposed in an arcuate plane with each shelf substantially normal to the slope of the plane at its particular position and in which illuminating means is disposed at a position whereby light therefrom strikes the entire area of each shelf.

In displaying merchandise, consisting of numerous small articles, in a cabinet it is desirable to make effective use of illumination. In this manner the merchandise is readily identified by an observer and his interest is aroused by the emphasis derived from the illumination. In illuminating shelving the light source is necessarily placed to the front, so that light may strike the goods and be reflected to the observer. The light source is also placed either well above or below the level of the shelves, so as not to obstruct the line of sight of an observer. In usual display cabinets the placement of the illuminating means is such that shelves fall in the shade of one another, such that only the front portions receive direct illumination. Thus, when the front of a shelf is emptied the remaining goods are not effectively illuminated.

In the present invention the shelving and the source of illumination are disposed in a relation that the direct rays of illumination strike the entire upper surface of each shelf as well as a substantial portion of the back wall behind the shelves. In this manner there is ensured proper illumination of goods on the individual shelves, whether the goods extend to the front of the shelves or are disposed only at the rear.

It is an object of this invention to provide a display cabinet in which goods may be shown under direct illumination.

It is another object of this invention to provide a display cabinet having shelving disposed with the entire upper surface areas in the direct illumination of a light source.

It is another object of this invention to provide a display cabinet that advantageously exhibits goods therein to aid sales of such goods.

It is another object of this invention to provide a display cabinet in which shelving forming a part thereof is disposed arcuately about a source of illumination.

These and other objects and advantages of this invention will appear in the description to follow. In the description reference is made to the accompanying drawing, forming a part hereof, in which there is shown by way of illustration and not of limitation a specific embodiment of the invention.

In the drawing:

Fig. 1 is a side view in elevation, with parts broken away and in section, of a cabinet embodying the invention,

Fig. 2 is a front view in elevation of the cabinet in Fig. 1, with parts broken away and in section, and

Fig. 3 is a fragmentary view of a portion of the cabinet viewed through the plane 3—3 indicated in Fig. 1.

Referring now to the drawing, the cabinet shown has a

shelf and at a height that the vision of an observer standing to the front is not obscured. With the illumination at such height and position the full area of the shelves is directly illuminated, without resort to either excessive depth to the cabinet, or shelves of insufficient width. Thus, as the supply of goods displayed on the shelves is depleted the remaining goods to the rear will not fall in the shadow of shelves above. The display of the goods, through illumination is not, therefore, impaired as the goods are removed. Further, the side panels have front edges sloping similarly as the rear wall of the display area whereby goods displayed may be viewed from diverse positions, while retaining shelves in arcuate array that do not shadow one another.

I claim:

In a display cabinet the combination comprising a pair of side wall members spaced from one another each having a forward edge that slopes from the front upwardly and rearwardly in an arc of increasing slope, with the edges falling in the same arcuate plane; a partial inner wall closely spaced to the side of each side wall member with the forward edge of each being of like configuration and set back slightly from the forward edge of the associated side wall member; a plurality of groups of pins protruding through the inner walls and each being of a length greater than the distance between the associated side wall and inner wall with a headed end positioned between the two associated walls; a partition wall extending between the side wall members presenting a curved surface spaced rearwardly of said forward edges of said side wall members sloping from its lower extent upwardly

and rearwardly with an increasing slope; illumination means including a pair of arms each extending forwardly from the upper limits of a forward edge of a side wall member to overhang such edge and a lamp supported by said pins at an angle substantially normal to the slope of the partition wall to receive light from the lamp over its entire upper surface area, each of said shelves having a depth not less than the distance between it and the adjacent shelves, the forwardmost edge of the lowest shelf being as far forward as said lamp, and the angle of tilt of each shelf allowing the shelf immediately beneath to be fully illuminated.
